UNITED STATES PATENT OFFICE.

LYMAN F. MUNGER, OF ROCHESTER, NEW YORK.

CHRONOMETER-ESCAPEMENT.

SPECIFICATION forming part of Letters Patent No. 289,551, dated December 4, 1883.

Application filed February 16, 1882. (No model.)

To all whom it may concern:

Be it known that I, LYMAN F. MUNGER, of Rochester, Monroe county, New York, have invented a new and Improved Method of Adjusting Chronometer-Escapements, of which the following is a specification.

The aim of my invention is to provide a simple, reliable, and expeditious mode for securing the proper relative position or adjustment of the several members of a chronometer-escapement when in the course of manufacture they are first assembled.

In the manufacture of chronometer-escapements as hitherto conducted great difficulty has been encountered in properly locating the escape-wheel, balance, and detent with respect to each other, and, as a consequence, such escapements have been expensive to build and troublesome to repair. The highest accuracy in the depth of the detent is necessary in order to permit the impulse-roller to swing freely between the teeth of the escape-wheel, and, as admitted by the best authorities, the most skillful workman is often obliged to "pitch" the detent two, three, or more times before arriving at the exact position required. In the course of this operation the workman, drilling one set of pivot-holes and finding them out of place, proceeds to fill them and bore new holes, and so on repeatedly, consuming a great amount of time and rendering the movement unsightly.

My invention, which obviates the above trouble and enables me to construct time-keepers possessing the excellent time-keeping qualities of the chronometer as cheaply as the ordinary time-keepers can be produced, consists simply in constructing the detent of a maximum or excessive length, then mounting the members of the escapement in approximately correct positions, and finally securing the exact adjustment by simply reducing the length of the detent until it permits the parts to assume the exact relative positions required. The reduction of the detent may be effected by hand-tools, or by any other convenient means; but it is preferred to make use of the peculiar instrument represented in the accompanying drawings.

Figure 1 represents a plan or face view of a chronometer-escapement. Fig. 2 is a side elevation of the same. Fig. 3 is a plan view of the special tool for reducing the length of the

detent. Fig. 4 is a diagram representing the relative positions of the escape-wheel, the impulse-disk, and the detent during the process of adjustment. Fig. 5 is an elevation of the detent detached.

A represents the escape-wheel; B, the balance; C, the impulse-roller; D, the detent-lever; E, the unlocking-pallet; G, the gold spring; *h*, the balance-wheel spring, and *k* the recovering-spring for the detent-lever. *I* is the banking-screw, *r* the detent-arm, and *s* the locking-stone. The escape-wheel and balance are so located relatively to each other that the balance receives an impulse from one of the teeth of the escape-wheel at each vibration of the balance toward the left in Fig. 1. The impulse-roller is notched or provided with an impulse-pallet adapted to receive motion from the teeth of the escape-wheel, the positions of the parts at the time of the impulse being represented by the dotted lines in Fig. 1. The detent *r* is supported by a staff, *t*, to which is affixed the detent-lever *D* and spiral recovering-spring *k*. The detent may be provided with the locking-stone *s*. The detent-lever is provided with the gold spring *G*, which is affixed to the outer end of the lever and extends a short distance beyond the inner end of the same into the path traversed by the unlocking arm or pallet *E*. The unlocking-pallet *E* vibrates with the balance, and on the forward vibration, in which the impulse is received from the escape-wheel, the pallet, striking the gold spring, causes the detent-lever and detent to swing into the position indicated by the dotted lines *G'* in Fig. 1 and unlocks the escape-wheel. After one tooth of the escape-wheel has passed the detent, the latter is returned to its locking position by the spiral spring *k*, and on the return vibration of the impulse-pallet the gold spring lifts, as represented in the drawings at *g'*, and permits the passage of the pallet. These operations are repeated at each vibration of the balance.

When in the course of manufacture the position of the escape-wheel and balance have been fixed, the diameter of the impulse-roller *C* is readily adjusted to that of the length of the teeth of the escape-wheel. To secure the proper action of the parts, the detent must hold the escape-wheel when at rest in such position that the teeth of the wheel will just clear

the periphery of the impulse-roller. To secure this adjustment with certainty and quickness, I make the detent in the first instance of a maximum length, or length slightly greater than required. Then, after having carefully located and seated the pivots of the detent-staff, I reduce the length, or, in technical language, the "depth" of the detent, until it permits the teeth of the escape-wheel to assume the correct position in relation to the periphery of the impulse-roller. The diagram, Fig. 4, represents in dotted lines the detent as originally made, and the corresponding position of the escape-wheel, and in full lines the correct depth of the detent and position of the escape-wheel with reference to the roller C.

It is to be understood that my method of adjustment is applied for the individual adjustment of each movement in the course of manufacture, and that the adjustment in each case being ordinarily different from that in the next, the skill and judgment of the operator must be exercised in each instance.

In reducing the length of the detent I prefer to make use of the grinding-machine represented in Fig. 3, which consists of a lap, L, mounted on an arbor, N, provided with a pulley, O, and with a spring, P, and screw R, whereby the arbor may be adjusted endwise to vary the position of the lap. The arbor is sustained in bearings on a suitable frame, which also carries at right angles to the arbor a revolving mandrel, S, to which the detent is attached in any convenient manner. By turning

the screw the position of the lap relatively to the mandrel—that is to say, the distance between them—may be changed, so that the lap will grind the detent to the precise length desired. The end face of the detent may be ground flat by preventing the rotation of the mandrel, or, by causing the mandrel to turn, it may be ground on a circle. The detent-lever is fitted to the detent-staff and held thereon by friction.

The present invention is limited to those matters which are hereinafter specifically claimed, and as to all features, devices, or combinations which may be described or shown, but not claimed, the right is reserved to make the same the subject of separate patents.

Having thus described my invention, what I claim is—

1. As an improvement in the art of manufacturing chronometer-escapements, the method of securing the relative adjustments of the members, consisting in constructing the detent of maximum or excessive length, assembling the parts, and finally reducing the length of the detent until it permits the parts to assume the required positions.

2. The mode of adjusting the position of the escape-wheel of a chronometer-escapement relatively to the impulse-roller, consisting in first mounting or assembling the parts and subsequently reducing the length of the detent.

LYMAN F. MUNGER.
